UNITED STATES PATENT OFFICE.

JOHN D. COX, OF BROOKLYN, NEW YORK.

CALENDAR.

Application filed October 27, 1926. Serial No. 144,584.

This invention relates to calendars and has particular reference to a changeable monthly calendar commonly termed a "perpetual calendar", and which is usable over a period 5 of years by adjusting or shifting the elements which bear indicia relating to the year, month and day.

It has been noted that calendars of this class which have been heretofore devised are 10 open to many objections, among which, for example, is the fact that the element bearing the indicia which represents the days of the month has no means for displaying the exact number of days.

15 It is therefore an object of the present invention to provide a shiftable element for concealing the indicia in excess of that needed for a given period so as to display the exact number of days in a given month.

20 The invention furthermore comprehends a calendar of the type set forth which includes means for displaying in a limited practical area the names of the months, the days of the month and the year date.

25 As a further object the invention comprehends a simple and effective manipulating means for shifting the elements together with guide indicia for facilitating the setting of the elements from the rear face of 30 the calendar casing.

Other objects reside in the simplicity of construction, economy with which the same may be produced, and the general efficiency obtained from the structure.

35 With the above recited and other objects in view, reference is had to the following specification and accompanying drawings in which there is exhibited one example or embodiment of the invention which is in no 40 way intended as a limitation upon the scope of the appended claims as it is to be clearly understood that variations and modifications which properly fall within the scope of said claims may be resorted to when found expedient.

In the drawings—

Figure 1 is a front view of a calendar constructed in accordance with the invention;

50 Fig. 2 is a rear view thereof;

Fig. 3 is a front view thereof with the face of the casing removed;

55 Figs. 4, 5, 6 and 7 are transverse sectional views taken approximately on the lines 4—4, 5—5, 6—6 and 7—7 of Fig. 3.

Fig. 8 is a vertical sectional view taken approximately on the line indicated at 8—8 in Fig. 3;

Fig. 9 is a face view of one of the month indicia-bearing elements;

Fig. 10 is a similar view of the other month indicia-bearing element;

Fig. 11 is a similar view of one of the day indicia bearing elements;

Fig. 12 is a similar view of the other day indicia-bearing element;

Figs. 13 and 14 are face views of the excess date concealing elements;

Fig. 15 is a face view of one of the year indicia bearing elements.

Referring to the drawings by characters of reference, the calendar comprises a casing including a front wall 10 and a rear wall 11, the confronting inner faces of which are recessed or channeled at 12 to provide marginal spacing portions or beads 13 affording a space for the reception of the elements which are confined therein. The front wall 10 is provided with window openings 14, 15 and 16, serving, respectively, as display windows for the name of the month, the days of the month and the year date. Indicia 17 representing the names of the month are printed, inscribed or otherwise provided on bearing elements 18 and 19, a plurality of 70 said bearing elements being employed for the purpose of allowing for the working of the calendar in a limited area. These bearing elements may be provided with additional indicia such as a number representing the 75 number of the calendar month and the number of days occurring in said month. The element 19 is arranged for sliding movement in the recess 12 of the rear wall 11 and is directly superimposed upon the inner surface 20 of the recessed portion of the rear wall. The element 18 is superimposed upon the element 19 and is cut away or rabbeted at 21 adjacent its upper edge so that when the member 18 is shifted to its lowest position the cut-away or rabbeted portion 21 registers with the window opening 14 to allow for the selective display of the indicia 17 of the superimposed element 19.

In order to assist in guiding the shifting 105 movements of the elements 18 and 19 as well as to provide manipulating means for shifting said elements, the rear wall 11 is provided with aligned pairs of slots 22—22, 23—23, and pins 24—24, 25—25, which are 110

anchored respectively in the elements 18 and 19, extend through the slots 22 and 23 and are formed with exteriorly disposed heads 26 and 27. The pins and slots further constitute means for limiting the shifting movement of the elements 18 and 19. The rear face of the rear wall 11 alongside of the upper slots 22 and 23, is printed, inscribed or otherwise provided with indicia 28 constituting means for guiding the user in setting the elements 18 and 19 to dispose the proper indicium 17 in registry with the window opening 14. The indicia or figures 29 representing the days of the month are printed, inscribed, or otherwise provided in rows and columns on bearing elements 30 and 31, said bearing elements being mounted in superimposed relation in the recess 12 of the rear wall 11 of the casing for transverse or lateral relative sliding movement. These bearing elements are independently guided and movable by pins 32 anchored in the bearing element 30 and extending through slots 33, the said pins having manipulating heads 34. Pins 35 having manipulating heads 36 are anchored in the bearing element 31 and extend into a transverse slot 37. Indicia 38 are printed, inscribed or otherwise provided adjacent the slot 33 for guiding the user in setting the element 30, while indicia 39 are printed, inscribed or otherwise provided on the rear face of the rear wall 11 adjacent the slot 37 for guiding the user in setting the bearing element 31. It will be noted that the indicia 29 on the bearing element 30 consisting of figures, are arranged in separated sets of columns and rows, so that upon relative shifting of the elements 30 and 31, a portion or all of the indicia on the element 30 is concealed by the element 31, when displayed through the window opening 15. By dividing the date indicia 29 unnecessary width of the casing is avoided.

In order to provide means for covering up, concealing or blocking out the date indicia in excess of that needed for a given month, a pair of laterally shiftable shields 40 and 41 are provided, the former being superimposed with respect to the bearing element 31 or arranged in front of said bearing, and the latter being arranged between the bearing elements 30 and 31. These shields are guided and manipulated by pins 42 and 43 anchored, respectively in the shields 40 and 41 and having manipulating heads 44 and 45, which are disposed exteriorly of the rear wall, the pins extending through the transverse slot 37. The shields 40 and 41 are further guided in their movement by slots 46 and 47, through which the pins 35—35 extend. A suitable chart 48 having indicia 49 is arranged adjacent the slot 37 with which the manipulating heads 44 and 45 co-operate to guide the operator

in setting the shields. If desired, suitable instructions 50 may be printed, inscribed, or otherwise provided on the rear face of the rear wall 11, for assisting the user in properly manipulating the heads of the pins. From this arrangement it is obvious that the shields provide means for concealing the date indicia in excess of that needed for a given length so that the calendar month displayed will have the exact number of days in a given month.

Stationary indicia 51 are arranged in a row at the upper portion of the window opening 15 relating to the names or abbreviations of the names of the days of the week so that the columns and rows of indicia 29 on the bearing elements 30 and 31 are provided with the usual headings.

Indicia or numbers 52 representing the years are printed, inscribed or otherwise provided on a pair of relatively shiftable bearing elements 53 and 54 mounted within the casing for lateral sliding movement and for selective registration with the window opening 16. Preferably the indicia 52 represent only the last two digits of the year number, indicia 55 representing the first two digits being carried by a stationary element 56 mounted in the window opening. The year indicia bearing element 54 is provided with an opening 57 which is adapted to register with the window opening 16 to allow for the display of the indicia 52 on the bearing element 53. The elements 53 and 54 are guided and shifted by means of pins 58 and 59 anchored, respectively, in said members, extending through a transverse slot 60 in the rear wall 11 of the casing, and provided with manipulating heads 61 and 62. The members 53 and 54 are provided with slots 63 and 64, respectively accommodating the pin shanks of the other member. The rear surface of the rear wall adjacent the transverse slot 60 is printed, inscribed, or otherwise provided with indicia 65 for guiding the user in setting the year indicia bearing members.

From the foregoing, it will be seen that a changeable monthly calendar has been devised, which is so constructed as to render the same usable over a period of years and which when so used allows for the display of the exact number of days in a given month.

What is claimed is:

1. A perpetual calendar including a pair of relatively shiftable superimposed elements bearing indicia representing the names of the month, a pair of relatively shiftable superimposed elements bearing indicia representing the numerical equivalents of the year dates, a pair of relatively shiftable superimposed bearing elements having rows and columns of figures representing the days of the month, and a casing having

window openings through which certain of the indicia on each of said pairs of bearing elements are selectively displayed.

2. In a perpetual calendar, including a casing having an opening for displaying elements bearing the rows and columns of indicia representative of the days of the month, a pair of relatively shiftable overlying elements, the outer one having a single set of contiguous sub-divided areas provided with numerals indicating the days of the month, the inner element having spaced groups of contiguous sub-divided areas provided with numerals representative of the days of the month, whereby upon relative shifting of said elements with respect to each other and with respect to the casing opening, the proper arrangement of the numerical equivalents of each month for every year may be obtained.

3. In a perpetual calendar, including a casing having an opening for displaying elements bearing the rows and columns of indicia representative of the days of the month, and having indicia representing the names of the days of the week adjacent an edge of the opening, a pair of relatively shiftable overlying elements, the outer one having a single set of contiguous sub-divided areas provided with numerals indicating the days of the month, the inner element having spaced groups of contiguous sub-divided areas provided with numerals representative of the days of the month, whereby upon rel-

ative shifting of said elements with respect to each other and with respect to the casing opening, the proper correlation of the rows and columns of numerals with respect to the indicia representative of the days of the week may be obtained for each month of any given year.

4. In a perpetual calendar, including a casing having an opening for displaying elements bearing the rows and columns of indicia representative of the days of the month and having indicia representing the names of the days of the month adjacent an edge of the opening, a pair of relatively shiftable overlying elements, the outer one having a single set of contiguous sub-divided areas provided with numerals indicating the days of the month, the inner element having spaced groups of contiguous sub-divided areas provided with numerals representative of the days of the month, whereby upon relative shifting of said elements with respect to each other and with respect to the casing opening, the proper correlation of the rows and columns of numerals with respect to the indicia representative of the days of the week may be obtained for each month of any given year, and a pair of relatively shiftable shield members respectively overlying the elements bearing the numerals representing the days of the month, for concealing the days of the month in excess of those needed.

JOHN D. COX.
